US00D524648S

(12) **United States Design Patent** (10) **Patent No.:** **US D524,648 S**
Feist et al. (45) **Date of Patent:** **** Jul. 11, 2006**

(54) **GELLED COMPOSITION APPLICATOR TIP**

(75) Inventors: **Mark W. Feist**, Colchester, CT (US); **Hans E. Haas**, Stow, OH (US); **Frank Marino**, Berlin, CT (US); **Thomas M. Polatas**, Munroe Falls, OH (US)

(73) Assignee: **Illinois Tool Works, Inc.**, Glenview, IL (US)

(**) Term: **14 Years**

(21) Appl. No.: **29/201,520**

(22) Filed: **Mar. 17, 2004**

(51) **LOC (8) CI.** **09-07**

(52) **U.S. Cl.** **D9/447**; D28/7

(58) **Field of Classification Search** D6/542;

D8/14.1; D9/434-435, 723-724, 440, 447; D23/259, 262; D28/7; 222/180-181.3, 320-321.1, 222/394, 448, 401.1, 401.13, 519-521, 566-571

(57) **CLAIM**

The ornamental design for a gelled composition applicator tip, as shown and described.

DESCRIPTION

FIG. 1 is a top, front, right perspective view of the gelled composition applicator tip;

FIG. 2 is a top plan view of FIG. 1;

FIG. 3 is a front elevation of FIG. 1; and,

FIG. 4 is a right side elevation of FIG. 1.

The broken lines in the drawing are for illustrative purposes only and form no part of the claimed design.
